CLAIM

The ornamental design for a knob for a vehicle joystick as shown and described.

DESCRIPTION

FIG. 1 is a front right perspective view of a knob for a vehicle joystick showing our new design.

FIG. 2 is a front elevation view thereof.

FIG. 3 is a back elevation view thereof.

FIG. 4 is a right elevation view thereof.

FIG. 5 is a left elevation view thereof.

FIG. 6 is a top plan view thereof; and,

FIG. 7 is a bottom plan view thereof.

The broken line in FIG. 7 illustrates a portion of the knob for a vehicle joystick that forms no part of the claimed design.

1 Claim, 7 Drawing Sheets
